A. M. HAUBRICH.
ELECTROMAGNETIC RELAY DEVICE,
APPLICATION FILED JULY 28, 1919.

Patented Oct. 17, 1922.

INVENTOR
ALEXANDER M. HAUBRICH

BY *S. Clyde Jones.*

ATTORNEY

UNITED STATES PATENT OFFICE.

ALEXANDER M. HAUBRICH, OF CHICAGO, ILLINOIS, ASSIGNOR TO THE STROMBERG-CARLSON TELEPHONE MANUFACTURING COMPANY, OF ROCHESTER, NEW YORK, A CORPORATION OF NEW YORK.

ELECTROMAGNETIC RELAY DEVICE.

Application filed July 28, 1919. Serial No. 313,754.

To all whom it may concern:

Be it known that I, ALEXANDER M. HAUBRICH, a citizen of the United States, residing at Chicago, in the county of Cook and 5 State of Illinois, have invented certain new and useful Improvements in Electromagnetic Relay Devices (Case 48), of which the following is a full, clear, concise, and exact description.

10 This invention relates to improvements in electromagnetic devices, and more particularly to electromagnetic devices of the inter-locking type.

The purpose of this invention is to provide 15 an inter-locking electromagnetic device for use in convertible switchboards, that is, a switchboard that is readily converted from magneto operation to central energy operation. Although the present invention is 20 primarily adapted for the purpose above outlined, it will be understood that it may be employed in other arrangements wherein inter-locking relays or electromagnets are employed.

25 In the drawings, Fig. 1 is a top view of the improved relay of this invention.

Fig. 2 is an end view, and Fig. 3 is a side view of the relay.

30 Fig. 4 represents diagrammatically portions of a telephone system wherein the present relay is employed.

Referring to the drawings, the numerals 1 and 2 designate electromagnets disposed in a parallel arrangement. Extending longitudinally of the electromagnets and immediately above them, are metal frame plates 3 and 4 which are bent at right angles at one end to form downwardly projecting arms, as indicated at 5. These arms abut 35 against the ends of the electromagnets and are securely clamped to them by threaded bolts, such as 8 and nuts (not shown). The electromagnets and frame plates when thus assembled are secured to mounting plate 7.

40 This mounting plate 7 is perforated in several places to provide outlets for the terminals 9 of the coils of the electromagnets. At the extreme end of the plates 3 and 4 and extending at right angles to the longitudinal axis of these plates, are the pins 10 and 11 which serve as axis for the angular armatures 12 and 13. These armatures are locked against removal from the plates 3 and 4, by screws 14. The armature 13 is

provided with a vertical upright 15 provided 55 with a notch arranged to be engaged by a spring 16. The spring 16 as well as the various other springs of the spring assembly, are separated by strips of insulation and fixed to the plate 4 by means of screws. The 60 armature 12 is provided with an up-standing Z-shaped member having a latterly extending arm 17 so positioned that when the armature 12 is actuated, arm 17 will raise the spring 16. The armature 12 also controls 65 several pairs of circuit controlling springs of the well known structure and arrangement which are secured to plate 3.

The operation of the relay is briefly described as follows: The electromagnet 2 is 70 energized to attract its armature 13, whereupon the spring 16 engages the notch in the upright 15, so that the armature 13 is mechanically held in an attracted position. The armature 13 remains in its locked position 75 until the electromagnet 1 attracts its armature 12, whereupon the arm 17 disengages the spring 16 from the notch of the upright 15, and the armature 13 assumes its normal position. 80

Fig. 4 of the drawings illustrate how the interlocking relay of the present invention may be used as a drop relay in a convertible switchboard, that is, a switchboard to be readily converted from magneto operation 85 to central energy operation. In Fig. 4, there are shown two subscribers' lines A and B, the first arranged for magneto operation and the second for central energy operation. When the interlocking relay is used with a 90 subscriber's line, similar to A, its electromagnet 1 is provided with two windings arranged to be included in series, but when this electromagnet is employed with a subscriber's line provided with common battery, 95 such as B, it need only be a single wound relay.

In order to more fully bring out the method of operation of the drop relay under consideration, the method of initiating calls 100 on two types of lines terminating at a convertible switchboard, will be described. When the subscriber at the local substation desires to initiate a call, he operates his magneto generator 25 in a well known manner and completes a circuit through contacts 26, conductor 27, lower armature and back contact of the electromagnet 1, winding of 105

2 electromagnet 2, upper armature and back contact of electromagnet 1, conductor 28, switchhook and its contact 29, back to the magneto generator 25. The electromagnet 5 2 is energized in this circuit and the spring 16 (Fig. 3) engages the upright member 15 to hold armature 13 of this electromagnet attracted. When the electromagnet 2 operates, a signal, such as lamp 30 functions to 10 inform the operator that a call is awaiting attention. The operator then inserts plug P into jack J' of the calling line. This closes a circuit from ground, through both windings in series of electromagnet 1, sleeve 15 of the jack J', sleeve of the plug P, winding of marginal relay 31, winding of relay 32, to ground. Electromagnet 1 and relay 32 are energized in this circuit, but the relay 31 is not operated in series with both windings of the electromagnet 1. The conductors 20 33 arranged for magneto operation are thus connected through the back contacts and armatures of relay 31 to the plug P. A supervisory conductor 34 is also extended to 25 the supervisory circuits for magneto operation. The completion of the call and the supervision of the same may be of any well known type and operation, and is therefore not described.

30 It will now be assumed that the subscriber at B whose substation is arranged for common battery operation, initiates a call by removing his receiver from its switchhook. This completes a circuit for electromagnet 2, which operates a line relay from grounded 35 battery, winding of this electromagnet, upper back contact and armature of electromagnet 1, conductor 35 through the switchhook and its upper contact, through the receiver and transmitter in series at substation B, conductor 36, and lower armature and back contact of electromagnet 1. The electromagnet 2 attracts its armature and closes an operating circuit for the line lamp 40 37. The operator on noting that lamp 37 is lighted, inserts the answering plug P in the jack J² of the calling line. It will be noted in the present case that the electromagnet 1 which operates as a cut-off relay has only one of its windings affected. As 45 soon as the answering plug is inserted in the calling jack, a circuit is closed from grounded battery, windings of relays 31 and 32 in series, sleeve of the plug P, sleeve 50 of the jack J², conductor 38, upper winding

of electromagnet 1, to ground. Since the upper winding of the electromagnet 1 is of relatively low resistance, this electromagnet as well as relays 31 and 32 are energized in series. The electromagnet 1 disconnects the line relay 2 in the well known manner and the marginal relay 31 connects the conductors 39 with the plug P for common battery operation. The extension, supervision and disestablishment of the connection may then proceed as in any well known common battery system.

While the relay of the present invention has been shown and described as a drop relay, it will be understood that it may be employed in any arrangement where interlocking relays are necessary.

What I claim is:—

1. In a relay, a pair of electromagnets, an angle armature and a spring assembly for each of said electromagnets, a latch mounted on the spring assembly of one of said electromagnets and functioning under certain conditions to hold the armature of said electromagnet locked, and means actuated by the armature of the other electromagnet for disengaging said latch.

2. In a relay, a pair of electromagnets mounted in the same plane, a pair of angle armatures for each of said electromagnets, a spring assembly located above each electromagnet, an extension attached to the armature of one electromagnet, a latch secured to the spring assembly of said last mentioned electromagnet and co-operating with said extension to lock its armature operated, and angular means carried by the other armature to disengage said latch.

3. In a relay, a pair of electromagnets mounted in the same plane, a pair of angle armatures for each of said electromagnets, a spring assembly mounted above each electromagnet to be actuated by its respective armature, a vertical extension attached to the armature of one electromagnet, a latch secured to the spring assembly of said last mentioned electromagnet and co-operating with said extension to lock its armature operated, said latch extending in the same direction as said spring assembly, and angular means carried by the other armature to disengage said latch.

In witness whereof, I hereunto subscribe my name this 24th day of July A. D. 1919.

ALEXANDER M. HAUBRICH.
